UNITED STATES PATENT OFFICE

2,444,991

FURNITURE

Edgar H. Hunter, Cambridge, Mass.

Application May 24, 1944, Serial No. 537,054

3 Claims. (Cl. 155—196)

1

This invention relates to an improvement in furniture, and particularly to a demountable chair.

The object of the invention is to provide a light weight article of furniture, such as a chair or settee, that can be moved or stored without requiring much space and which can be quickly and easily set up for use. The nature of the invention will best be understood from the following description of an illustrative embodiment thereof shown in the accompanying drawings.

In the drawings:

Fig. 1 is a perspective view showing a chair embodying the invention;

Fig. 2 is a top plan view of the chair shown in Fig. 1;

Fig. 3 is a side view, and

Figs. 4 and 5 are detail views of parts of said chair.

The chair shown in the drawings has a curved seat 1 pivoted as by hinges 2—2 to a curved back 3 which is so formed that its rear surface matches the curve of the undersurface of the seat. The seat 1 has curved side pieces 4—4 and the back has similar side pieces 5—5. The bottom of the seat and the rear part of the back may be made of plywood or other suitable sheet material 6 fastened to the edges of the side pieces. A seat cushion 7 and a back cushion 8 are preferably used, especially where the chair is to serve as an easy chair. The back and seat are supported by two crossed members 9 and 10, each of which, as shown in Figs. 4 and 5, has a middle connecting part 11, two legs 12 and 13, and a back supporting projection 14. The inner edge 15 of the projection 14 is curved to match the curve of the back, and the upper edge 16 of the connecting portions 11 is curved to match the underside of the seat. Approximately in the middle of each connecting part is a substantially vertical slot. In one supporting member the slot 17 extends upwardly from the bottom edge of the support, as shown in Fig. 4, while in the other member the slot 18 extends downwardly from the seat supporting edge as shown in Fig. 5.

In assembling the chair, the two supporting members are placed in crossed position so that each of the slots engages the uncut parts of the other supporting member and the supports are held in interlocked position. After the crossed

2

supports are in place, the hinged back and seat are fastened to the supports, as by a suitable slip connection 19, in the position required by the curved supporting edges. This construction makes it possible to use plyboard (preferably 5-ply or more) or other suitable sheet material for the supports, seat and back, thus cutting the cost of manufacture and reducing the number of separate parts needed.

When the chair is taken down, the back and seat are lifted off the supports and folded so that the rear of the back touches the underside of the seat, and the crossed interlocked supports are separated and placed side by side. These three pieces may then be moved or stored while laid out flat, requiring very little moving or storage space.

I claim:

1. A demountable chair having, in combination, a pair of vertical plate-like crossed supporting members each having upper curved generally horizontally and vertically extending seat and back supporting edges and having integrally formed thereon a back leg and a front leg, a pair of cooperating notches formed in said members which are interlocked to hold said members in said crossed position, a seat having a bottom surface conforming to the curvature of said seat supporting edges, a back rest having a rear surface conforming to the curvature of said back supporting edges, said rear surface being adapted to fit against the bottom surface of said seat, hinges connecting said back rest and seat at the junction of said rear surface and said bottom surface, and side elements on said back and said seat having abutting end edges when on said supporting members, said hinges being operable to swing said back and seat from the position in which said end edges abut to a position in which the rear surface of the back rest lies nested adjacent the under surface of the seat when said back and seat are removed from said supporting members.

2. A demountable chair having, in combination, a seat having a curved bottom surface, a back rest having a curved rear surface conforming to the curve of the seat bottom, a hinge connecting the lowermost rear surface of the back and the rearward edge of the bottom of the seat, a pair of integrally formed vertically and horizontally

extending supporting members for said seat and back having supporting surfaces conforming to the curve of said seat and back which hold said seat and back against pivoting about said hinge, cooperating notches in said supporting members which hold said members rigidly in crossed position, and means for holding said seat from slipping forwardly on said supports, said back and seat being adapted when removed from said supporting members to pivot about said hinges to 10 nest together with the rear surface of the back adjacent the under surface of the seat.

3. A demountable chair having, in combination, a hingedly connected seat and back supported on vertical plate-like crossed seat supporting members having upper curved generally horizontally and vertically extending seat and back supporting edges, and side pieces on said seat and on said back, having matching end edges which abut to hold said back and seat in position when 20 on said supporting members, said seat and back having curved lower and rear edges conforming

to the curvature of the supporting edges adapted to fit together in nested relationship when said chair is dismantled and the back and seat are swung rearwardly about said hinge connection.
